GRID CONSTRUCTION

Zed J. Atlee, Elmhurst, Ill., assignor to General
Electric X-Ray Corporation, Chicago, Ill., a
corporation of New York

Application July 3, 1945, Serial No. 603,031

5 Claims. (Cl. 250—27.5)

1

The present invention relates in general to electron flow devices and has more particular reference to devices including radio, X-ray and similar tubes for use in electronic systems.

Electronic flow devices of the character mentioned frequently include, as a part thereof, a grid element for the purpose of controlling electron flow between anode and cathode elements of the device, electrons being emitted from the cathode and passing to the anode under the control of the grid, during the operation of the device. Under the circumstances, any primary or secondary electron emission by the grid may interfere with the desired control accomplished by the grid, particularly where the flow device is designed or adapted for high voltage operation.

An important object and purpose of the present invention is to provide an improved grid structure for electron flow tubes particularly those employed for high voltage operation; a further object being to provide a grid that is substantially, if not entirely, incapable of emitting electrons.

Another important object is to provide a grid that is incapable of either primary or secondary electron emission and hence is inert in that respect.

Another important object is to provide a suitable inert grid material, as in the form of wire, having adequate stiffness permitting it to be formed and arranged to provide a satisfactory grid having adequate mechanical strength.

Another important object is to provide a grid material comprising platinum or beryllium or an alloy embodying both platinum and beryllium either alone or alloyed with traces of other materials; a further object being to utilize a grid element comprising zirconium carrying a surface filament of zirconium oxide, to form a substantially inert grid.

The foregoing and numerous other important objects, advantages, and inherent functions of the invention will become apparent as the invention is more fully understood from the following description, which, taken in conjunction with the accompanying drawings, discloses a preferred embodiment of the invention.

Referring to the drawings:

Fig. 1 is a sectional view through an electron flow device embodying a grid formed in accordance with the teachings of the present invention;

Fig. 2 is a perspective view of the grid;

Fig. 3 is an end view of the grid shown in Fig. 2; and

2

Fig. 4 is a sectional view taken along the line 4—4 in Fig. 2.

To illustrate the invention, the drawings show a three-element electron flow device 10 comprising a sealed envelope 11, which may be made of glass, an electron emitting cathode 12, an anode 13 spaced from the cathode, and a grid 14 interposed between the anode and cathode, said anode, cathode and grid being supported within the envelope 11.

The device 10 may be operated by energizing the cathode for electron emission and by applying a suitable electrical potential between the anode and the cathode to drive electrons, emitted by the cathode, to the anode, control of electron flow being accomplished by applying a controlling potential to the grid. The anode, cathode and grid may, of course, have any suitable or preferred form for the purpose of accomplishing their respective functions. As shown, the grid may comprise a cage enclosing the cathode 12, said cage comprising wire 15 arranged in loops supported by spaced apart end members 16 and 17. The member 16 may comprise a band of metal having spaced, dependent lugs 18 integrated therewith and forming a means for mounting the cage on suitable support means within the envelope. The cage member 17 may also comprise a generally cup-shaped metal member having a central opening 19 and additionally spaced apart openings 20 disposed around the central opening. The wire 15 may comprise a single strand arranged upon the members 16 and 17 in serpentine fashion forming loops extending therebetween and secured thereto to form a generally tubular cage. Each end of the wire and the several looped portions thereof may be welded, brazed, or otherwise fastened and electrically connected to the members 16 and 17. An additional wire 21 of material similar to that of the wire 15 may be arranged in helical fashion upon the stretches of the wire 15 between the support members 16 and 17, the wire 21 being preferably welded and thus electrically connected with the wire 15 at each crossing thereof.

The grid 14 may be mounted upon and electrically connected to a metal supporting member 22, preferably comprising molybdenum, nickel or steel, which is welded or otherwise connected at one end to the lugs 18. At its other end, the member 22 may be integrated, as by welding, to a plate 23, which in turn is fastened, in integral fashion, to the bottom of a metallic cup 24 having edges forming a glass-to-metal seal

with the open end edges of a preferably re-entrant sleeve portion 27 of the envelope. The grid may be electrically connected in a suitable electrical circuit outwardly of the envelope by means of a metallic stud 31 having a metal head 28, preferably screw threaded to the stud as by means of a threaded socket 29 in the head, and a threaded stud portion 30 adapted to removably fasten the stud to the head, the head 28 being electrically connected, as by welding the same to the member 24, which preferably comprises a ferrous material having a high nickel content to render the same readily sealable with the glass envelope.

The upper end of the grid 14 may be mounted on a support stem 32 having a portion extending in the opening 19 to center the grid on the stem. The stem 32 may also form an insulated mounting for filaments comprising the electron emitting cathode 12. The cathode may be connected in a filament energizing circuit outwardly of the envelope by suitable conductor means extending outwardly through a suitable seal construction 33 at one end of the tube; and the anode 13 likewise may be connected in circuit outwardly of the envelope by means of an electrical conducting anode mounting including a stud 34 extending outwardly of the envelope through a suitable seal 35.

In order that the grid 14 may be constituted as an element incapable of electron emission, the wires 15 and 21 and the end members 16 and 17 may be made of a suitable inert material, although it is not essential, for practical purposes, to make the end members of absolutely inert material. The end members consequently may comprise relatively inert material such as molybdenum. The wires 15 and 21, however, comprise material which is incapable of electron emission. To this end, the wires 15 and 21 may be made of pure platinum. For many purposes, however, pure platinum may not have adequate mechanical strength, particularly where employed in wire form, and it is preferable, therefore, to incorporate beryllium with platinum in order to obtain added strength and rigidity.

The inert grid material may also comprise beryllium alone or a beryllium-rich alloy, and the present invention contemplates a grid comprising either pure platinum, or pure beryllium, or alloys including platinum or beryllium, particularly the alloy of platinum and beryllium. More specifically, the preferred material is an

alloy of platinum containing a relatively small amount of beryllium in quantities of the order of 0.1 per cent, just sufficient to impart adequate strength and rigidity in the grid material.

Exceedingly satisfactory results may be obtained by utilizing zirconium as a substantially inert grid material, the invention, in this connection, contemplating the employment of a grid comprising zirconium metal, either in pure form or alloyed with traces of platinum or beryllium, or both, the zirconium material being oxidized to form a surface film of zirconium oxide, thereby affording a grid structure substantially incapable of electron emission even at high temperature.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An inert grid comprising a foraminous screen of beryllium.
2. An inert grid comprising an alloy of beryllium with platinum.
3. An inert grid comprising a network of beryllium wire.
4. An inert grid comprising an alloy of beryllium with platinum forming a foraminous screen.
5. An inert grid comprising a network of wires formed of an alloy of beryllium with platinum.
